UNITED STATES PATENT OFFICE.

EMIL KRENZLER, OF BARMEN, GERMANY.

BRAIDING MACHINE.

Application filed October 8, 1925, Serial No. 61,165, and in Germany October 21, 1924.

The present invention relates to so-called single-thread braiding machines, that is, to those machines for the manufacture of braided lace wherein the individual bobbins or pairs of bobbins may be arrested in their passage by the aid of jacquard gear and can thereby be excluded from the braiding operation.

In braiding machines of this kind as heretofore constructed, having regard to the sizes of coils generally employed for the manufacture of braided lace, the pitch, that is the distance between the centres of adjacent plates must, in the case of machines with fixed plates, amount to at least 60 mm., and in the case of machines with plates formed to serve simultaneously as drivers the distance between the centers of adjacent plates must be at least 55 mm., and these prior machines work at a comparatively low speed of about 140-160 revolutions per minute, because at a higher speed violent shocks occur owing to the continued intermittent arrest and re-insertion of the bobbins, which shocks lead to the machine becoming prematurely worn and to the threads being readily broken.

Now the present invention is essentially based on recognition of the fact that those dimensions of the bobbin which, according to prevailing opinion with regard to the waste of time and work occurring at the exchange of the bobbins, should not be reduced, can nevertheless be chosen very considerably less and therefore the remaining dimensions of the machine can be substantially reduced, when it is a matter of working up thin thread-material such as is employed for the manufacture of fine braided lace, or in other words that it is advisable to employ for the manufacture of lace from fine thread-material not the braiding machines hitherto usual but instead of employing them to construct and use a special braiding machine of very substantially smaller and hitherto unknown dimensions.

I have therefore devised a machine in which the parts are so combined, arranged and proportioned that the pitch distance between centers of adjacent driver plates is reduced to a pitch below 50 mm., and, in fact, may be reduced to a pitch as low as 32 mm., or lower, with corresponding reductions in size of the bobbins and the

thread. In consequence, not only are the space requirements and weight of the machine as well as the cost of manufacture lessened, but also, in consequence of the smaller dimensions, the path of travel of the bobbins necessary to produce an interengagement of threads and therefore the centrifugal and accelerating forces are very substantially reduced so that the speed and consequently the output of the machine may be very considerably increased without the danger of injurious shocks or breakage of the threads arising. On the other hand the new machine is characterized by quiet running and small power consumption and wear to an extent hitherto unattained. In addition to the above, owing to the reduced pitch the plates are brought into close proximity to the centre line of the braiding machine. The free length of the thread is therefore less and the braiding threads have less tendency to sag, in consequence of which the extra thread-tensioning otherwise necessary to prevent sagging is avoided and it becomes possible to work up substantially finer kinds of thread.

Moreover, in consequence of this reduction, it has been made possible, to arrange a number of these new machines directly adjacent to one another on one and the same frame. The small size of the machine therefore permits a single attendant from a single point of observation to easily inspect the whole of the bobbins of the machine and to reach or exchange them. On the other hand not only is each individual machine more fully in view than heretofore, but, because of the joint assembly of a group of the machines, one and the same attendant can watch considerably more machines or bobbins than heretofore, with a saving in the number of employees. Finally, in part owing to the reduction of dimensions, and in part owing to a number of machines assembled together in one group and to the elimination of passage-ways hitherto required between individual machines, the space-requirements are very considerably reduced and the driving gear made considerably less costly.

For carrying out the invention in practice the machines principally suitable are those single-thread braiding machines of known construction wherein the bobbin-drivers are

driven only when the bobbins are to operate and wherein the gaps in the drivers are so formed that arrested drivers coact to guide the bobbins at the crossing-points in the track. In such a construction a specially small pitch between centers of drivers, namely that of 30-35 mm., is possible.

An embodiment of the present invention is illustrated by way of example in the accompanying drawings wherein,

Fig. 1 is a diagrammatic side elevation of the new braiding machines with their essential parts shown diagrammatically,

Fig. 2 a front elevation of a group of four braiding machines with common operating machinery,

Fig. 3 a vertical section of a portion of the track of the braiding machine, shown in about actual size, and

Fig. 4 a plan view of a portion of the track.

Referring to the drawings, in the example shown the common machine-frame comprises a number of columns 1 extending down to the floor and intermediate columns 2 which are connected together by longitudinal bars 3 and at their upper ends carry the base-plates 4 of the several braiding machines. Each of those braiding machines is provided in the usual manner with a top plate 6 serving for guidance of the conventionally illustrated bobbins 5 and is furnished with a suitable jacquard gear 7, draw-off rolls 8 and reeling device 9. The driving means comprise a counter-shaft 11 journaled below the frame and driven through a pair of gear-wheels 12 by an electromotor 13, and connected by separate belt-drives 14 with the four individual braiding machines. Behind each of these belt-drives 14 is provided in known manner a disengageable coupling, not shown, whereby each of the several braiding machines may be individually thrown into and out of action.

The construction of the individual braiding machines, as is specially clear from Figs. 3 and 4, may be conveniently so chosen in known manner that the plates 15 mounted at the level of the top plate 6 serve simultaneously as drivers and are provided with gaps for receiving and guiding the bobbins. Driving is effected, likewise in known manner, by a gear wheel 17 running continuously on the fixed column, the upper edge of which wheel is provided with a clutch face 18 for engagement with a movable clutch member 19. This movable clutch member 19 is slidable on a sleeve 20 of the plate 15 coupled to turn with said half-coupling and obtains its sliding movement from a fork 24 controlled by the jacquard rod-connections 21, 22 and the spring 23. Said fork when at the level shown, that is, in the uncoupled position, engages by means of its

lug 25 in a groove 26 in the lower side of the plate 15 and thereby secures the driver-plate and with it the bobbin in their normally inactive positions, i. e., positions of rest.

As seen from Figs. 3 and 4 which show actual size, the bobbin 5 and coil 30 thereon are substantially smaller than hitherto used in braiding machines and to just the same extent are the remaining dimensions of the machine made correspondingly smaller, so that the pitch, that is, the distance between two adjacent plates amounts in the particular machine disclosed, to only 32 mm., as Fig. 4 shows.

Since owing to the plates being made smaller, the pitch-circle diameter, that is, the circle whereon the entire row of plates is arranged, is correspondingly smaller, that angle at the centre of the machine which is formed by adjacent threads from the bobbins remains the same and an always accurate action of the beaters for driving up and firmly holding the thread-crossings is ensured. On the other hand, owing to this reduction in dimensions, the track of the bobbins is substantially shortened and the centrifugal and accelerating forces are reduced, so that a considerably higher speed of the machine is possible and easy and quiet running is guaranteed.

Obviously, the invention is not limited to the embodiment shown, but other embodiments of the invention are possible, in particular, there might be arranged on a common machine-frame, instead of four of the individual machines, more or less than this number if desired.

What I claim is:

1. The combination, in a single-thread braiding machine, of a raceway plate, and a group of raceway carriers on the raceway plate, said carriers having a pitch less than 50 mm. from center to center of adjacent carriers throughout the group.

2. The combination, in a single-thread braiding machine, of a raceway plate, and a group of raceway carriers on the raceway plate, said carriers having a pitch of substantially 30 to 35 mm. from center to center of adjacent carriers throughout the group.

3. The combination, in a single-thread braiding machine, of a raceway plate, and a group of disk-shaped raceway carriers on the raceway plate, each having a pair of diametrically disposed peripheral driving recesses, said carrier disks having a pitch less than 50 mm. from center to center of adjacent carriers throughout the group.

4. The combination, in a single-thread braiding machine, of a raceway plate, and a group of disk-shaped raceway carriers on the raceway plate, each having a pair of diametrically disposed peripheral driving recesses, said carrier disks having a pitch of 130

substantially 30 to 35 mm. from center to center of adjacent carriers throughout the group.

5. In a multi-braiding machine structure, a frame, a plurality of single-thread braiding machines mounted on said frame, each machine including a raceway plate and a group of carriers mounted thereon, the car-

riers of each machine having a pitch from center to center of adjacent carriers not exceeding 35 mm., a single-driving means, and a separate jacquard drive mechanism for each machine actuated by said driving means. ¹⁰

In testimony whereof I affix my signature.
EMIL KRENZLER.
